UNITED STATES PATENT OFFICE.

HENRY AUGUST DECHENNE, OF WOBURN, ILLINOIS.

MOP-WRINGER.

SPECIFICATION forming part of Letters Patent No. 568,895, dated October 6, 1896.

Application filed June 27, 1896. Serial No. 597,213. (No model.)

To all whom it may concern:

Be it known that I, HENRY AUGUST DE-
CHENNE, a citizen of the United States, resid-
ing at Woburn, in the county of Bond and
5 State of Illinois, have invented a new and
useful Mop-Wringer, of which the following
is a specification.

This invention relates to mop-wringers, and
the object in view is to provide a simple and
10 efficient device of this character attached to
and forming a part of the pail or bucket and
comprising spaced rollers, one of which is di-
vided intermediate its ends to admit of the
shank or handle of the mop being passed lat-
15 erally between the rollers, thus adapting the
mop to be drawn upwardly through or be-
tween the rollers for wringing said mop, there-
by obviating the necessity of forcing the mop
downward between the rollers and spilling
20 the dirty water upon the floor.

Other objects and advantages of the invention
will appear in the course of the ensuing
description.

The invention consists in certain novel fea-
25 tures and details of construction, as herein-
after fully described, illustrated in the draw-
ings, and claimed.

In the accompanying drawings, Figure 1 is
a perspective view of a bucket or pail, show-
30 ing the improved wringer therein. Fig. 2 is
a sectional view of the same. Fig. 3 is a de-
tail view showing one of the springs for ac-
tuating the yielding roller.

Similar numerals of reference designate cor-
35 responding parts in the several figures of the
drawings.

1 designates a pail or bucket, which may
be either of wood or metal. For the purpose
of carrying out the present invention a roller-
40 supporting frame 2 is provided, said frame
being arranged within the bucket and at or
near the top edge thereof and occupying about
one half of the top of the bucket, the remain-
ing half of the bucket being left free for the
45 insertion of the mop.

The frame 2 is preferably constructed of a
single piece of strap metal, the central por-
tion of which is secured to the inside edge of
the pail. From this central portion parallel
50 arms 3 extend toward the diametrical line of
the pail, where they are bent in opposite di-
rections and extended so as to reach the inner

wall of the pail, to which they are securely
attached at the points 4. Diagonal braces 5
are interposed between the outer ends of the 55
arms 3 and the inner wall of the bucket for
giving the necessary rigidity to the frame 2.
The arms 3 are provided with longitudinal
slots 6, and these slots receive slidingly the
opposite ends of the spindle 7 of a wringing-
60 roller 8. At each end of the roller 8 is ar-
ranged a spring 9, one arm of which connects
with the spindle of the roller 8 and the other
end with the frame 2 or other fixed point.
The tension of these springs is exerted to force 65
the yielding roller 8 toward the second roller.

The second roller 10 is arranged parallel
with the roller 8, and is journaled near the
outer ends of the arms 3. This roller is di-
vided at about a central point, thus forming 70
the roller into two sections, each section be-
ing journaled on an independent spindle 11.
The adjacent ends of the two sections of the
roller 10 are spaced apart sufficiently to ad-
mit the shank or handle of the mop, so that 75
the mop may be passed between the rollers
and drawn upward without the necessity of
first pushing the mop downward between the
rollers.

The mop containing the dirty water is in-
80 troduced into the unoccupied half of the pail,
and the shank or handle of the mop is then
moved laterally between the ends of the roller-
sections until it strikes against the roller 8.
By now drawing the mop upward the dirty 85
water is wrung therefrom and deposited in
the bottom of the pail, the roller 8 yielding
to allow the upward movement of the mop,
but pressing with sufficient force against the
same to remove the dirty water. This obvi-
90 ates the necessity of pushing the mop down-
ward between the rollers and spilling the
water on the floor.

It will be apparent that changes in the form,
proportion, and minor details of construction 95
may be resorted to without departing from
the spirit or sacrificing any of the advantages
of this invention.

Having thus described the invention, what
is claimed as new is—

1. The combination in a mop-wringer, of
parallel rollers, one of said rollers being
formed in two sections independently jour-
naled and having their adjacent ends spaced

apart, substantially as and for the purpose described.

2. The combination in a mop-wringer, of a horizontal U-shaped frame arranged in the upper portion of a pail and having its terminal portions bent to form attaching-ears by which said frame is secured to the pail, and parallel rollers journaled in said frame, one of said rollers being formed in two sections to independently journaled, and having their

adjacent ends spaced apart, substantially as and for the purpose described.

In testimony that I claim the foregoing as my own I have hereto affixed my signature in the presence of two witnesses.

HENRY AUGUST DECHENNE.
